AMUSEMENT DEVICE

Felix Alva, New York, N. Y.

Application February 2, 1938, Serial No. 188,382

5 Claims. (Cl. 272—8)

This invention relates to devices useful in the performance of tricks of pretended magic and, more especially, to improvements in means for discharging cards or the like from an apparently empty receptacle such as a hat.

It is among the more important objects of the present invention to provide a new and improved device for receiving and substantially automatically subsequently discharging a plurality of sets 10 of cards from an apparently empty receptacle such as a hat, a box or a similar container.

It is another object of the present invention to provide a device of the type hereinbefore referred to characterized in that it functions at a predetermined time interval after setting, thereby causing discharge of cards or the like from a receptacle or container when said receptacle or container is arranged so as to preclude manual operation by the user.

20 It is another object of the present invention to provide a device of the nature referred to wherein set means are included for discharging a first set of cards from the receptacle or container and later discharging a second set therefrom at a predetermined time interval from the discharge of the first set.

Notable among the features of the device according to the present invention is that it can be substantially concealed within a hat or similar 30 container, thereby providing the appearance of emptiness thereto, but will subsequently and automatically erect itself for discharge of cards.

It is also a feature of the device according to the present invention that it is compact and 35 relatively simple to manipulate, thereby enhancing and facilitating its useful employment in tricks of mock magic.

It is also noteworthy of the device according to the present invention that it comprises a relatively small number of parts, is formed of relatively inexpensive material and is comparatively simple to fabricate, thereby permitting concomitant economies of manufacture and/or repair.

45 Other objects, advantages and features of the device according to the present invention will be apparent to those skilled in the art during the course of the following description wherein a specific embodiment of the present invention, herein illustrated, will be described, it being clearly understood however that the illustrated preferred embodiment is given solely by way of example and is non-limitative.

In the drawings:

55 Fig. 1 is substantially a vertical sectional view

of the preferred form of device embodying the present invention, shown in position within a hat-like container;

Fig. 2 is substantially a rear elevational view of the preferred embodiment of the present invention with a portion of the casing thereof removed to show the interior mechanism and with a 5 spring member in extended position;

Fig. 3 is a rear elevational view with part of the casing removed, similar to Fig. 2, except the 10 spring member is shown in retracted position and certain interior parts are omitted for clearness; and

Fig. 4 is a vertical sectional view of Fig. 3, 15 taken along the line 4—4.

Regarded in certain of its broader aspects, the device according to the present invention comprises a plurality of receptacles adapted to receive cards or the like and means associated with said receptacles whereby cards can be intermittently discharged therefrom at a predetermined time. Regarded from a somewhat less broad viewpoint, the device according to the present invention comprises a structure of the type hereinbefore referred to wherein spring-pressed 20 members are substantially automatically successively tripped, thereby flipping or otherwise ejecting cards, positioned in said receptacle, therefrom.

In order to facilitate a clearer understanding 30 of the matter of the present invention, the illustrated embodiment thereof will be hereinafter described.

Referring then to the drawings, the numeral 10 generally designates a hat-like structure or receptacle wherein the device is positioned, the device itself being generally indicated by the numeral 11. It will be understood, of course, that the type of receptacle to be used in conjunction with the device according to the present invention depends to great extent upon the requirements of the user and, solely for purposes of illustration, a hat is employed in the embodiment of the present invention shown in the drawings.

The device itself, designated by the numeral 11, comprises a body 12 mounted on the bottom portion 13 of the member 10 by means including bearings, one of which is designated at 14. A spring 15 connected to a loop 15a, formed in a portion of the body and attached to a support 15b mounted on the member 13, tends to move said body member 12 from horizontal to vertical position, that is to say from the position shown in full line in Fig. 1 to the position shown in phantom. This movement of the member 12 is 45 50 55

normally restricted by means including a trip lever 16 having a bent end portion 17 adapted to serve as a latch and engaging with a portion of the member 12 fulcrumed near the place generally designated at 18 and provided with an outwardly extending handle portion 19, whereby the user or operator of the device can manipulate said lever arm, thereby permitting said spring 15 to move said body 12 from horizontal 10 into substantially vertical position. Control mechanism, generally indicated at 20 and hereinafter described, is also mounted on a side portion of the hat or other receptacle, substantially as shown in Fig. 1.

Referring now to Figs. 2, 3 and 4, it will be seen that the device 11 comprises a casing comprising a front portion 21, a back portion comprising the members 22 and 23, side portions 24 and 25 and a bottom 26. The top of the casing 20 is open and substantially unobstructed but is divided by partition member 27 mounted on the sides 24 and 25 positioned substantially parallel to the back and front portions and extending through said body 12 from the top thereof to a place near the bottom 26, being terminated in an upturned box-like portion including the parts 28 and 29 substantially as shown. It will be observed that the partition 27 and the front 21 define a receptacle 30, the bottom of which comprises a ledge or shelf-like member 31 attached to said front part 21, said receptacle being adapted to receive a plurality of cards, certain of which are designated at 32.

A resilient spring-like member 34 mounted on a pin 35 positioned on a part of the partition member 27, normally tending to move the free end portion thereof to the upper part of the partition by means including a coil spring 37, is formed on the end thereof to provide a hook-like member 38 adapted to strike and eject cards 32 from said receptacle during the course of the upward movement of said hook-like end portion. The hook-like end portion of the member 34 is, however, normally held beneath the bottoms of the cards 32 and the ledge 31 by means including a pivoted latch member 39 having a projecting formation 40 near the top thereof adapted to engage with said hook-like part of the member 34 and restrict the upward movement thereof. The member 39 is pivoted on the pin 41. It will be noted that the member 39 normally tends to move in a clockwise direction, as shown in Fig. 2, by means including a coil spring 42 attached to said lever at the place generally designated at 42a. The end portion of the lever is bent to provide a part 45 having an opening formed therein adapted to receive but not engage with the slidable bar-like member 46 to be hereinafter described.

Bottom portion 28 of the receptacle, defined 60 by the partition member 27 and the back part 22 in the body member, serves as a support for a flat resilient spring-like member 50 which is pivoted thereto as at 51, substantially as shown, and, when in extended position, would normally 65 at least tend to move the free end portion of said member 50 to a position outside the receptacle. The free end portion of the member 50 is attached, as for example by means of a pivot or similar fastening means 52, to a sliding crossbar 53 positioned within slot-like cutaway portions designated at 54 and 54a, formed in the members 22 and 27, respectively. Although it will be seen that the member 50 normally tends to move the crosspiece 53 toward the upper portion of the slots 75 54 and 54a, it will also be observed that this

movement of the member 53 can be at least largely prevented by engagement of said member with the hook-like portion 56 of the lever 57 pivoted on the pin 58 and normally held against the stop 59 by means including a coil spring 60 5 attached to said lever arm at the place generally designated at 61. Although in Figs. 2 and 3 only one of the levers 57 is shown, it will be observed upon scrutiny of Fig. 4 that a pair of these levers is provided, one on each side of the receptacle 10 defined by the walls 22 and 27 and engaging with projecting end portions of the crosspiece 53, substantially as shown, said levers 57 being associated with each other by means including a crosspiece 57a. Cards 63 positioned within said receptacle 15 rest upon said crosspiece 53 whereby, upon disengagement of the hook-like portion 56 from the end parts of said crosspiece, said cards will be forcibly ejected from said container by means including the resilient spring-like member 50. 20

Upright standards 70 and 71 attached to the front and back 21 and 23 and the sides 24 and 25 of the casing or body member, are provided with openings formed therein adapted to slidably hold the bar-like member 46 substantially as 25 shown. It will be noted that the end portion 46a of said bar-like member projects through an opening formed in the side 25 and that a collar 72 is fixedly attached and carried on said bar-like member 46 and is arranged to abut against a resilient spring-like member 73 whereby said bar-like member will normally be moved to cause said collar to abut against the upright standard 71, substantially as is shown in Figs. 2 and 3. It will also be noted that the bar-like member 46 carries 35 fixedly attached thereon a collar 74 adapted to abut against parts of and actuate the lever 39 hereinabove described. A spring-pressed U-shaped member, generally designated at 75 and comprising side parts 76 and 77, united by a cross-piece 78 mounted on the member 46 by means including a pin 79, is normally held in substantially the position shown in Figs. 2 and 3 by means including coil springs 80 and 81 mounted on said pin 79 and engaging with parts of the side members 76 and 77. It will be observed that a stop 82 attached to said side parts and adapted to abut against the bar-like member 46, at least tends to limit the counter-clockwise rotative movement of said member 75. It will be noted that during sliding movement of said bar-like member, said member 75 will engage with the pivoted lever arm 57, substantially as will be hereinafter described.

The control mechanism generally designated 55 at 20 comprises a so-called delayed release mechanism, such as is commonly used in photographic cameras and the like, and comprises a gear box 85 mounted on a supporting member 86, the latter of which is formed with a forked end 87 adapted to engage with and hold a portion of a cable release 88 having a projecting tongue-like member 89 which, when the members are assembled in the relationship shown, is positioned adjacent an operating plunger 90 of the delayed release 65 mechanism. It will be noted that the opposite end of the cable release 88 is provided with a threaded end part adapted to engage with a threaded bushing in the side 24 of the body of the device, substantially as shown in Figs. 2 and 70 3, whereby as the delayed release mechanism 20 functions, the projecting portion 91 of the cable 88 abutting against an end part 92 of the bar-like member 46 at least tends to move same against the force of the spring 73. It will, of 75

course, be understood that the delayed release mechanism employed in conjunction with the device according to the present invention will be of the type wherein the actuating plunger 99 moves outwardly from the gear box 85 to depress plunger 89 of the cable release at a predetermined time interval from the time of setting, and that after the cable release mechanism has been actuated a predetermined time interval will elapse before pressure is released therefrom and the member 90 retracted into the gear box 85. Accordingly, it will be seen that during operation the bar-like member 46 is moved toward the right, as illustrated in Figs. 2 and 3, and subsequently moved toward the left, the first movement being caused by the positive action of the delayed release mechanism and the second movement being caused by the positive action of the spring 73 in conjunction with the retracting movement of the delayed release mechanism.

In operation, the delayed release mechanism generally designated at 20, is set and started in operation. It will, of course, be understood that the body proper of the device generally designated at 12 will be positioned substantially horizontally, as in Fig. 1, being held in said position by means including the lever arm 16 as hereinbefore described. After demonstrating to the spectators that the hat or receptacle is apparently empty, the operator then positions the receptacle so that the interior thereof is not visible to the audience and by depressing the end portion 19 of said lever 16, the body 12 of the device is moved into substantially vertical position as shown in phantom in Fig. 1. Meanwhile the delayed release mechanism 20 has been functioning and at a predetermined time interval after commencement of operation of said mechanism, the bar-like member 46 will be moved toward the right of the device as shown in Figs. 2 and 3, thereby causing the collar 74 to engage with the portion 45 of the trip lever 39 and moving said lever in a counter-clockwise direction and releasing the hooked end portion 38 from engagement with the portion 40 of said lever, whereby cards positioned within the receptacle, defined by the front portion 21 and the partition 27, will be flipped or ejected therefrom as the free end portion of the member 24 moves upwardly in the manner hereinabove referred to.

As the member 46 continues in its movement toward the right, as illustrated in Figs. 2 and 3, the U-shaped member 75 rides over the end portion of the trip levers 57 and springs up behind same by reason of the coil springs 81 associated with said U-shaped member as hereinbefore described. At a predetermined time interval thereafter the plunger 90 of the delayed release mechanism is retracted within the gear box 85, thereby permitting the bar-like member 46 to be moved leftwardly, as illustrated in Figs. 2 and 3, by means including coil spring 73 acting against the collar 72 mounted on said bar-like member. As the bar-like member moves toward the left, the U-shaped member 75 engages with the trip levers 57, it being noted that although counter-clockwise rotative movement of said members is precluded, clockwise rotation thereof is not; hence, as the member 46 moves toward the left as aforesaid, said arms 57 are moved in a clockwise direction, thereby disengaging the end portions 56 thereof from connection with the projecting parts of the crossbar 53, whereby cards 63 positioned within the receptacle defined by the back 22 and partition 27, are ejected therefrom through means in-

cluding the resilient compressed spring-like member 50 hereinbefore described.

It will be observed then that during operation of the device, after displaying the receptacle to be apparently empty, certain cards are first ejected from one of the receptacles at a predetermined time interval after commencement of operation and that subsequently thereto, and at a predetermined time interval thereafter, other cards are forcibly and positively ejected from another receptacle within the device.

It is to be understood that this improvement is capable of extended application and is not confined to the exact showing of the drawings nor to the precise construction described and, therefore, such changes and modifications may be made therein as do not affect the spirit of the invention nor exceed the scope thereof as expressed in the appended claims.

What is claimed is:

1. A device of the type described comprising a box-like casing, a relatively fixedly mounted partition within said casing dividing the interior thereof into a first and a second compartment, means for positively ejecting cards and the like positioned in said first compartment therefrom, means for positively ejecting cards and the like positioned in said second compartment therefrom, and means for intermittently actuating said ejecting means associated with said first compartment and for actuating said ejecting means associated with said second compartment at a predetermined spaced time interval after actuation of ejecting means associated with said first compartment.

2. A device of the type described comprising a box-like casing, a relatively fixedly mounted partition within said casing dividing the interior thereof into a first and a second compartment, means for positively ejecting cards and the like positioned in said first compartment therefrom, comprising a spring-pressed arm, a hook element carried on an end of said arm adapted to sweep through said first compartment and engage with cards therein during movement of said arm into extended position, a first latching means engaging with portions of said arm for holding same in retracted position, means for positively ejecting cards and the like positioned in said second compartment therefrom, comprising a spring-pressed bar vertically slidably in said casing whereby said bar engages with cards positioned in said compartment as it moves to extended position, a second latching means engaging with portions of said bar for holding same in retracted position, and means for actuating said first and second latching means at predetermined spaced time intervals.

3. A device of the type described comprising a container having a base portion, supporting members carried on said base portion, a box-like casing, supporting means connecting said members and said casing whereby at least some rotative movement of said casing relative to said container is permitted, a relatively fixedly mounted partition within said casing dividing the interior thereof into a first and a second compartment, means for positively ejecting cards and the like positioned in said first compartment therefrom, comprising a spring-pressed arm mounted at one end of said partition, a hook element carried on the other end of said arm adapted to sweep through said first compartment and engage with cards therein during movement of said arm into extended position, a first latch-

ing means engaging with portions of said arm for holding same in retracted position, means for positively ejecting cards and the like positioned in said second compartment therefrom, comprising a spring-pressed bar vertically slideable in said casing in slot-like openings formed in sides thereof whereby said bar engages with cards positioned in said compartment as it moves to extended position along said slots, a second latching means engaging with portions of said bar for holding same in retracted position, and means for actuating said first and second latching means and associating said arm and bar respectively from engagement therewith at predetermined spaced time intervals.

4. A device of the type described comprising a box-like casing, a relatively fixedly mounted partition within said casing dividing the interior thereof into a first and a second compartment, means for positively ejecting cards and the like positioned in said first compartment therefrom comprising a spring-pressed arm, a hook element carried on an end of said arm adapted to sweep through said first compartment and engage with cards therein during movement of said arm into extended position, a first latching means engaging with portions of said arm for holding same in retracted position, means for positively ejecting cards and the like positioned in said second compartment therefrom, comprising a spring-pressed bar vertically slideable in said casing whereby said bar engages with cards positioned in said compartment as it moves to extended position, a second latching means engaging with portions of said bar for holding same in retracted position, means for actuating said first and second latching means at predetermined spaced time intervals comprising a spring-pressed slideable rod, means for imparting substantially uniform reciprocating movement of predetermined rate to said rod, means comprising a relatively stationary lug carried on said rod engaging with said first latching means whereby as said rod is moved in one direction said latching means is actuated and said spring-pressed arm is released, and means comprising a spring-pressed lug carried on said rod engaging with said latching means and adapted to actuate same, releasing said bar only when said rod is moved in a direction opposite from that causing actuation of said first latching means whereby during the reciprocation of said rod said first latching means is actuated and, at a predetermined time interval

thereafter, said second latching means is actuated.

5. A device of the type described comprising a container having a base portion, supporting members carried on said base portion, a box-like casing, supporting means connecting said members and said casing whereby at least some rotative movement of said casing relative to said container is permitted, a relatively fixedly mounted partition within said casing dividing the interior thereof into a first and a second compartment, means for positively ejecting cards and the like positioned in said first compartment therefrom, comprising a spring-pressed arm mounted at one end of said partition, a hook element carried on the other end of said arm adapted to sweep through said first compartment and engage with cards therein during movement of said arm into extended position, a first latching means engaging with portions of said arm for holding same in retracted position, means for positively ejecting cards and the like positioned in said second compartment therefrom, comprising a spring-pressed bar vertically slideable in said casing in slot-like openings formed in sides thereof whereby said bar engages with cards positioned in said compartment as it moves to extended position along said slots, a second latching means engaging with portions of said bar for holding same in retracted position, means for actuating said first and second latching means and associating said arm and bar respectively from engagement therewith at predetermined spaced time intervals, comprising a spring-pressed slideable rod, means for imparting substantially uniform reciprocating movement of predetermined rate to said rod, means comprising a relatively stationary lug carried on said rod engaging with said first latching means whereby as said rod is moved in one direction said latching means is actuated and said spring-pressed arm is released, and means comprising a spring-pressed lug carried on said rod engaging with said latching means and adapted to actuate same, releasing said bar only when said rod is moved in a direction opposite from that causing actuation of said first latching means whereby during the reciprocation of said rod said first latching means is actuated and at a predetermined time interval thereafter said second latching means is actuated.

FELIX ALVA.
